HOLDER FOR BOBBINS.

Richard D. Sedgewick, Durham, N. H.

Application April 16, 1947, Serial No. 741,815

4 Claims. (Cl. 242—130)

1

This invention relates to a novel bobbin holder or creel for use in hand-knitting a variegated Argyle pattern or any other pattern which calls for several supplies of yarn in continual use, each of which is at times, or intermittently, incorporated in the fabric being produced.

Variegated Argyle patterns call for yarns of a plurality of different colors, usually five, and to avoid longitudinal lengths of yarn across the inside of the work from end to end thereof, while knitting a tubular fabric, yarn of each color is wound on two bobbins so that ten loaded bobbins are employed, the strands of all of which are continuously connected with the work. Heretofore, these ten strands and their bobbins would continually become entangled with the result that considerable time and effort was expended in disentangling them.

The invention has for its object to provide a bobbin-holding device, for use while producing variegated hand-knitted fabrics, which will be of simple, inexpensive and efficient construction.

It is also an object of the invention to provide a device of the character referred to whose use, while hand-knitting a variegated pattern, will obviate the above noted objectionable entanglement of the yarns and bobbins heretofore characterizing this operation.

A further object of the invention is to provide a novel bobbin which will be particularly constructed for application to my new holder.

To these ends I have provided a bobbin holder of the character described which, in the preferred embodiments of the invention, may be constructed as set forth in the following description, the several novel features of the invention being particularly pointed out and defined in the claims at the close of the description. The invention also contemplates, as a new article of manufacture, a bobbin attachment for application to the holder just referred to.

In the accompanying drawings:

Figure 1 illustrates the use of a bobbin holder embodying one form of the invention.

Figure 2 is a side elevation, full size and partly broken away, of the bobbin holder shown in Fig. 1.

Figure 3 is a top plan view of the bobbin holder and bobbins shown in Fig. 1.

Figure 4 illustrates the construction of a bobbin suitable for use with the holder shown in Figs. 1, 2 and 3.

The bobbin holder illustrated in Figures 1, 2 and 3 of the drawings is made from a single angulated length of round spring wire bent to form an elongate body 9 made up of two rows of loops 10

2

and 11 formed as obtuse isosceles triangles whose sides 16 are common to the loops of both rows, the loops 10 being aligned longitudinally along and constituting one marginal portion of the body, and the loops 11 being aligned longitudinally along and constituting the opposite marginal portion of said body.

An end portion 12 of the wire at one end of body 9 is a part of the loop 11 at that end and is bent laterally toward the opposite marginal portion of the body with its extremity formed into an eye 13 that is disposed in immediate proximity to the adjacent acute bend of the loop 10 at said end, said eye and bend providing a pair of bobbin-gripping jaws as will appear later.

So also, the free end portion 14 of the wire which is part of the loop 10 at the opposite end of body 9 is bent laterally toward the opposite marginal portion of the latter and has its extremity formed into an eye 15 that is disposed in immediate proximity to the adjacent acute bend of the loop 11 at that end of the body, said eye and bend providing a pair of bobbin-gripping jaws as will also appear later.

The loops of each row 10 and 11 are disposed in close proximity to each other thereby to enable each pair of opposed acute bends of the loops to serve as bobbin-gripping jaws also. As will presently appear, each pair of opposed acute bends of the loops provide between them a slit into which a loaded bobbin of sheet material can be forced edgewise so that it is held against displacement when the body 9, Fig. 2, is lifted by means of the strands of yarn extending therefrom to the fabric being constructed. The slits just referred to are disposed at opposite sides of the body 9 in two longitudinal rows with the slits of each row alternating longitudinally with the slits of the other row.

For use with the above described holder I may provide a plurality of bobbins 20 like that shown in Fig. 4 of the drawings, each made from any suitable sheet material such as cardboard, thin sheet metal or the like and characterized by the provision adjacent to one end thereof of an aperture or hole 17 and a hook 18 spaced apart a predetermined distance to serve as presently to be described. This bobbin may have the form of a prolate annulus with the hole 17 and hook 18 disposed upon opposite sides of the longer axis of the bobbin as shown. A slit 21 formed through one side of the bobbin provides a laterally resilient arm 22 which permits a supply of yarn to be wound upon the opposite side of the bobbin as indicated at 23 by dotted lines in Fig. 4 and as

shown by full lines in Figs. 1 and 3, said arm being bent aside as each convolution is wound into place.

Ten bobbins are provided for the holder shown in Figs. 1, 2 and 3 and in applying each to the holder the same is presented edgewise into the entrance between two acute bends of the holder as indicated by dotted lines in Fig. 2, with the hook 18 foremost whereupon it is forced into position between said two bends until hook 18 is 10 in engagement with the portion 19 of the triangular loop that is occupied by the bobbin (Fig. 4) and the two opposed acute bends occupy the opposite ends of the hole or aperture 17. The resilience of the wire permits the bobbin to be thus applied to the holder and when in position thereon the bobbin is held quite securely against displacement relatively to the holder but can be removed readily through the application of force.

Use of the above described holder prevents tangling of the strands and bobbins not only while knitting on the pattern but also when the work is temporarily laid aside. Each row is knitted from right to left on the needle while the holder and its bobbins may be resting on the lap of the knitter, and as a row is completed the work and rack are lifted slightly and turned 180 degrees before knitting from right to left along the other side of the work during which operation the holder is resting again upon the lap of the knitter. This turning of the work and holder is a simple and orderly movement because the holder is light and mobile and holds the yarn and bobbins in order at all times.

What I claim is:

1. A bobbin-holder for use while hand-knitting a fabric, said holder comprising a single elongated mobile body unit of substantially greater width than thickness and formed along a marginal portion thereof with a row of spaced-apart 40

transversely disposed slits for holding a plurality of loaded bobbins of sheet material in orderly spaced-apart relationship while the yarns of said bobbins are connected with the fabric and the latter is being moved about.

5 2. A bobbin-holder of the class described according to claim 1 wherein each slit communicates at its inner end with a relatively large aperture provided in said body unit.

15 3. A bobbin-holder for use while hand-knitting a fabric, said holder comprising a single elongated mobile body unit of substantially greater width than thickness and formed along its opposite side marginal portions with two rows of transversely disposed bobbin-holding slits, and with the slits of each row off-set longitudinally relatively to the slits of the other row.

20 4. A bobbin-holder of the class described according to claim 3 wherein each slit communicates at its inner end with a relatively large aperture provided in said body unit.

RICHARD D. SEDGEWICK.
